Inventor
Joseph B. Oakley

UNITED STATES PATENT OFFICE.

JOSEPH B. OKEY, OF INDIANAPOLIS, INDIANA.

STOVE-COVER, POT, AND PAN LIFTER.

Specification forming part of Letters Patent No. 59,058, dated October 23, 1836.

To all whom it may concern:

Be it known that I, JOSEPH B. OKEY, of Indianapolis, in the county of Marion and State of Indiana, have invented a new and useful Stove-Cover, Pot, Plate, and Pan Lifter; and I do hereby declare that the following is a full, clear, and exact description of the construction of the same, reference being had to the annexed drawing, making a part of this specification.

The said lifter is to be made of iron or any other suitable metal.

To enable others skilled in the art to make and use my invention, I proceed to describe its construction.

It consists of a metallic head, A, having a number of hooks (represented at E, F, G, H, &c.,) and two holes, one at the front and one

at the rear of the head, at D and D, to receive the handle B; also a small V or other shaped pin at L, to keep the handle from turning in the head. The handle is pinned on the head by the pin at K in such a manner as to make it perfectly secure.

Having fully described the character of my improvement, what I claim as my invention, and seek to secure by Letters Patent, is—

A metallic head, constructed substantially as set forth, in combination with a wooden or other handle, in the manner and for the purpose herein set forth.

J. B. OKEY.
